UNITED STATES PATENT OFFICE.

CHARLES B. RIMMEL, OF CARNEGIE, PENNSYLVANIA, ASSIGNOR OF ONE-HALF TO PETER J. SCHEIB, OF CARNEGIE, PENNSYLVANIA.

MINER'S LAMP.

No. 920,882.

Specification of Letters Patent.

Patented May 4, 1909.

Application filed February 13, 1909. Serial No. 477,597.

To all whom it may concern:

Be it known that I, CHARLES B. RIMMEL, a citizen of the United States of America, residing at Carnegie, in the county of Allegheny and State of Pennsylvania, have invented certain new and useful Improvements in Miners' Lamps, of which the following is a specification, reference being had therein to the accompanying drawing.

10 This invention relates to miners' lamps, and the primary object of the invention is the provision of novel means in connection with the lamp for heating the illuminating grease thereof, thus preventing the same from coagulating or becoming in such a condition that the wick of the lamp cannot absorb the same.

A further object of this invention is to provide a heating conductor in connection with 20 a miner's lamp that will obviate the necessity of lining the same with copper or a similar heat conductor.

I accomplish the above objects by providing a simple and durable heat conductor that 25 can be used in connection with the present type of lamp for insuring a continuous burning of the wick thereof after the wick has been ignited. As the mining laws require that a grease be used in lieu of an illuminating oil, considerable trouble has been experienced in maintaining the grease in proper condition to be absorbed by the wick. It is the present practice generally to provide the lamp with a copper lining which adds expense to the manufacture of the lamp. I 30 obviate the necessity of using a copper lining and at the same time provide a heat conductor that will be positive in its action and which may be used for adjusting the wick 35 when the wick is extinguished.

The invention will be hereinafter described in detail and reference will now be had to the drawing, wherein I have illustrated the preferred embodiment of the invention, but it is 45 to be understood that the structural details thereof can be varied or changed without departing from the spirit and scope of the invention.

In the drawings, Figure 1 is an elevation of 50 a lamp constructed in accordance with my invention, Fig. 2 is a vertical sectional view of the same, and Fig. 3 is a cross sectional view of the spout of the lamp taken on the line X—X of Fig. 2.

In the accompanying drawings, 1 designates the body of the lamp having a hook 2 whereby it can be attached to a cap; a hinged lid 3 for closing the body, and a tapering spout 4.

My invention resides in providing the 60 spout 4 with a tube 5, said tube being preferably attached to the inner upper side of the spout and extending from one end thereof to the other. In the tube 5, I arrange a copper wire or heat conductor 6 which protrudes from the upper end of the tube and is bent upon itself, as at 7, whereby the flame from the wick (not shown) placed in the spout 4 will engage the projecting portion of the wire 6, and the latter will conduct the 70 heat to the opposite end of the wire, which protrudes in to the contents of the body 1.

In some instances, the tube 5 can be loosely mounted in the spout, particularly in connection with lamps at present used. It 75 is obvious that when the wick of the lamp is not ignited, that the wire conductor 6 can be manipulated to move the wick in the spout.

Having now described my invention, what I claim as new, is;—

1. The combination with a lamp body having a spout and a tube located therein, of a wire located in said tube and having one end lying within the chamber of the lamp body and the other end projecting beyond 85 the spout, the ends of said wire being bent at right angles to the body of the wire and in opposite directions to each other.

2. In combination with a lamp body having a spout, and a tube located within the 90 spout on one wall thereof and extending throughout the length of said wall, of a wire arranged for longitudinal movement in said tube, the said wire having its outer end extending beyond the end of the spout and 95 bent at right angles to the body of the wire so as to overlie the spout end, the inner end of the wire projecting into the chamber of the lamp body and being also bent at right angles to the body of the wire.

In testimony whereof I affix my signature in the presence of two witnesses.

CHARLES B. RIMMEL.
